UNITED STATES PATENT OFFICE

HARVEY E. HERR, OF BUFFALO, NEW YORK, ASSIGNOR TO HERR MANUFACTURING CO., INC., OF BUFFALO, NEW YORK, A CORPORATION OF NEW YORK

HOLDER FOR SPINNING RINGS

Application filed March 16, 1928. Serial No. 282,183.

This invention relates to certain novel improvements in the holders or mountings employed in connection with the spinning rings of spinning machines.

One of its objects is the provision of a holder for self-oiling spinning rings having means which not only constitutes a track or bearing surface for the bar traveler, but which also forms an effective guard for preventing the thread coming into contact with the lubricated zone of the spinning ring.

Another object of the invention is to so design the holder that the bar traveler is effectually held against accidental displacement from the spinning ring and prevented from tipping inwardly against the bobbin or take-up spool.

In the accompanying drawings:—

Figure 1 is a top plan view of a spinning ring holder embodying my invention. Figure 2 is an enlarged transverse section thereof on line 2—2, Figure 1. Figure 3 is an enlarged fragmentary transverse section on line 3—3, Figure 1. Figure 4 is a side elevation of the holder.

Similar characters of reference indicate corresponding parts throughout the several views.

In spinning machines of the character to which my invention is particularly applicable, the threads to be twisted are delivered by feed rolls (not shown) to a take-up spool 10 and traversing the same is a vertically-reciprocating bar 11, the spool extending through an opening 12 in the bar.

Mounted on the reciprocating bar 11 and surrounding the take-up spool is a supporting member or holder 13 for the spinning or traverse ring 14 upon which the customary bar traveler 15 is adapted to revolve. During the operation of the machine, the bar traveler assumes a substantially upright position and revolves with and about the take-up spool, the threads passing under the traveler before being wound upon the spool, and the traverse bar 11 being reciprocated so that the threads are uniformly wound upon the spool in layers. Rising from the outer edge of the base or attaching flange 16 of the spinning ring holder are yieldable brackets 17

having lugs 18 formed thereon which form seats or ledges for supporting the spinning ring a suitable distance above the top of said base flange. The inner edge of the latter terminates in an upwardly-facing annular flange or neck 19 which is spaced from the opposing inner edge of the spinning ring 14 to provide an annular channel 20 for receiving the depending legs of the bar traveler in the manner shown in Figure 3. The space between the base flange of the holder 13 and the spinning ring communicates with the channel 20 and forms a lateral continuation thereof, and the lower side of the spinning ring is slightly flared or beveled upwardly and outwardly to provide a bearing face for the bar traveler.

For the purpose of lubricating the bar traveler, the spinning ring 14 is preferably made hollow to form a lubricant chamber 21 having a restricted passage 22 at its inner edge for supplying the necessary amount of lubricant to such edge and thence to the bar traveler, the lubricant flowing by gravity and aided by centrifugal force to the lower free ends of said traveler which engage the lower bearing face of the spinning ring. In its top the latter has a filling opening 23.

The neck 19 of the spinning ring holder 13 is provided with a rim or extension 24 which extends above the lubricant passage 22 of the spinning ring and substantially to the top side thereof, and which is preferably flared outwardly, as shown, to provide an overhanging wall at the upper end of the annular, traveler bar channel 20, as clearly shown in Figures 2 and 3. The upper edge of this flared rim is preferably rounded and polished and in addition to the bottom face of the spinning ring 14 constitutes a track or bearing face for the bar traveler. By constructing the holder in this manner, a safety guard is provided which effectually prevents the threads being guided by the bar traveler on to the take-up spool from dropping into the oil zone of the spinning ring and soiling them. Furthermore, it positively limits the inward tipping movement of the bar traveler and prevents the latter from coming in contact with the bobbin and injuring the thread.

In addition to these characteristics, the flared extension 24 of the holder forms a locking rim which effectually retains the bar traveler in its channel 20 and avoids any possibility 5 of it jumping out of its operative position.

While possessing the several advantages above pointed out, this improved holder is no more expensive than the one heretofore employed, it increases the efficiency of the 10 machine to which it is applied and it positively and effectually overcomes one of the greatest objections to thread-spinning, that of contaminating the thread with lubricant. By meeting this objection, this holder affords 15 a great saving to the manufacturer as regards the waste of material due to lubricant soiling.

I claim as my invention:—

1. A device of the character described, comprising a supporting member containing 20 a central opening through which a take-up spool is adapted to extend, a spinning ring for a bar traveler mounted on said supporting member, and a safety guard rising from the supporting member through the spinning 25 ring for holding said bar traveler out of contact with the take-up spool, said guard terminating at its upper end in an outwardly flaring rim forming an inner bearing face for the bar traveler.

30 2. A device of the character described, comprising a supporting member, a spinning ring for a bar traveler mounted thereon and having a lubricant reservoir containing a lubricant-passage in its inner edge, and an 35 annular flange rising from said supporting member and extending through the spinning ring, said flange terminating above the lubricant passage of the spinning ring.

3. A device of the character described, 40 comprising a supporting member, a spinning ring for a bar traveler mounted thereon and having a lubricant reservoir containing a lubricant-passage in its inner edge, and an annular flange rising from said supporting 45 member and extending through the spinning ring, the upper portion of said flange being flared outwardly and terminating above the lubricant-passage of the spinning ring.

4. A device of the character described, 50 comprising a supporting member, a spinning ring for a bar traveler mounted thereon and having a lubricant reservoir containing a lubricant-passage in its inner edge, and an outwardly-flaring annular flange rising from 55 said supporting member and extending through the spinning ring to a point above its lubricant-passage, the upper edge of said flange being rounded and forming a bearing face for the bar traveler.
